INTERNAL COMBUSTION ENGINE

Arthur L. Reeves, Caron, Saskatchewan, Canada

Application April 23, 1936, Serial No. 76,053

1 Claim. (Cl. 123—79)

My invention relates to internal combustion engines and an object of the invention is to provide a device of the character herein described in which is used a single master valve in each cylinder together with a sliding sleeve surrounding the piston to open and close the exhaust and intake ports of the cylinder.

A further object of my invention is to provide a device of the character herein described having a single mushroom valve requiring only a very small travel to open sufficiently to allow the free passage of gases and thereby reduces the hammering of valves, cams and rocker arms encountered in the conventional type of engine.

15 A further object of my invention is to provide a device of the character herein described which reduces the amount of power taken from the crank shaft by the valves by using only one valve instead of two as in the usual type of internal combustion engine.

20 A further object of my invention is to provide a device of the character herein described in which the side ports are isolated during the firing stroke.

25 A further object of my invention is to provide a device of the character herein described having a single master valve around which pass both the hot exhaust gases and the cool intake gases, the valve thereby warming and aiding vaporization of the intake gases and cooling to some extent the exhaust gases.

30 A still further object of my invention is to provide a device of the character herein described which is simple to construct and will not easily become out of order.

35 With the above more important objects in view and such other minor objects as may appear as the specification proceeds, my invention consists essentially in the arrangement and construction of parts all as hereinafter more particularly described, reference being had to the accompanying drawings, in which—

Fig. 1 illustrates a vertical central section of my invention with the rocker arm shown in full.

40 Fig. 2 shows a vertical section of a further embodiment of my invention taken on the line 2—2 of Figure 5.

45 Fig. 3 shows a still further embodiment of my invention taken on the line 3—3 of Figure 4.

50 Fig. 4 illustrates a horizontal section taken on the line 4—4 of Figure 3.

Fig. 5 illustrates a horizontal section taken on the line 5—5 of Figure 2.

55 Fig. 6 illustrates a plan view of the embodiment shown in Figure 1.

Fig. 7 is a fragmentary vertical section taken on the line 7—7 of Figure 5.

Fig. 8 is a detail view of the method used for attaching the reciprocating arm for rotating the sleeve used with the embodiment of my invention 5 illustrated in Figure 3.

In the drawings like characters of reference indicate corresponding parts in the different figures.

My invention consists of a housing 1 composed of a lower outwardly bulging crank case 2 which converges to a vertically disposed cylinder casing 3. The cylinder casing it will be noted, has double walls, an inner wall 4 and an outer wall 4' with passageways 5 therebetween. These passageways are for the purpose of providing a water jacket around the central cylinder formed by the inner wall 4.

Upon the upper annular surface 6 of the cylinder casing is placed a gasket 7 and surmounting thereon is the cylinder head 8 having a configuration as shown in the drawings accompanying this application. This cylinder head is also double walled and passageways 9 are provided therein to receive water for cooling purposes. The cylinder head 8, it will be noted, extends well into the cylinder formed by the inner walls of the cylinder casing 4 but has a diameter somewhat smaller than the internal diameter of the cylinder formed by the walls 4 thus leaving a space 10 between the cylinder head and the walls 4 for a purpose later to be explained.

Centrally disposed within the lower end of the cylinder head is a valve seating 11 leading upwardly into a chamber 12 thereabove from which extends a laterally and upwardly extending diverging passageway 13 to the side of the cylinder head.

A vertically extending orifice 14 is passed through the center of the cylinder head and a bushing 15 having an upper flange 16 is inserted therein. Through the center of the bushing extends a valve stem 17 to the lower end of which is attached a large mushroom valve 18 designed 45 to engage with the seating 11 on the under side of the cylinder head.

The upper end of the valve stem 17 is threaded and a nut 19 having an outwardly extending flange 20 is threadably attached thereto. Interposed between the flanges 16 on the bushing 15 and the flanges 20 is a compressed helical spring 21 which tends to keep the valve 18 in engagement with the seating 11. Adjustment of the pressure exerted by the spring may be accom- 55

plished by changing the position of the nut 19 upon the threaded portion of the valve stem.

Surmounted upon the upper surface of the valve head are standards 22 which carry a horizontally disposed shaft 23 upon which is pivotally mounted a rocker arm 24 obliquely disposed with relation to the shaft 23. One end of the rocker arm is formed into a head 25, the lower surface 26 of which is designed to bear against the upper end of the valve stem 17. The opposite end of the rocker arm is provided with a threaded orifice 27 therethrough and a threaded shank 28 is passed into the orifice. The upper end of this shank is furnished with a diametrically located groove 29 for the reception of a screwdriver and the lower end thereof is spherically formed as at 30 to form a ball for a ball and socket joint. In order that the shank 28 may be maintained in any position desired, a locking nut 31 is also provided.

Within the gear casing 2 is furnished a horizontally disposed cam shaft 32 upon which is located a cam 33 having a configuration as best illustrated in Figure 9. A push rod 34 extends between the cam 33 and the spherical head 30 of the shank 28 and is provided at its lower end with a tappet in the form of a roller 35 maintained in position by a pin 36 passing through the bifurcated lower end of the rod.

To the top end of the rod is affixed a head 37 with an upwardly opening socket 38 therein having a semispherical lower surface 39 to receive the spherical head 30 on the shank 28. This head is maintained in contact with the socket and the roller 35 in engagement with the cam 33 by means of the spring 21 upon the shank 17.

It should here be mentioned that the cam shaft 32 is geared to the crank shaft of the engine in the usual manner and is designed to rotate at one half the speed of the crank shaft.

Within the cylinder formed by the walls 4 is inserted a snugly fitting cylindrical sleeve 40. The upper end of this sleeve is received into the space 10 between the cylinder head and the walls 4 and encircling the spherical portion of the head are furnished piston rings 41 and similar rings 42 are placed around the outer surface of the cylinder 40 to engage with the walls 4.

Integral with the lower end of the cylinder 40 is provided a laterally extending arm 43 in the outer end of which is formed an internally threaded vertically disposed orifice 44. A second tappet 45 is threaded into this orifice and is maintained in position therein by a lock nut 46. A roller 47 is provided within the bifurcated end of the tappet and engages with a cam or eccentric 48 also mounted upon the cam shaft 32.

Within the upper part of the crank case 2 and 60 in alignment with the longitudinal axis of the tappet 45 is a tapped orifice 49 into which is placed a bolt 50 which protrudes slightly past the lower surface of the crank case. Interposed between the crank case and the arm 43 and enclosing the protruding ends of the bolt 50 and the tappet 45 is a compressed helical spring 51 which tends to maintain the roller 47 in engagement at all times with the cam 48.

Within the sleeve 40 is inserted the usual type 70 of piston 52 and protruding from the lower end thereof is the conventional connecting rod 53 pivotally attached to the piston by the wrist pin 54.

Extending through the cylinder walls 4 and 4' 75 are a pair of passageways to be used as intake

and exhaust ports, the lower passageway 55 being the exhaust port and the upper passageway 56 the intake port.

Passing through the sleeve 40 and in alignment with the passageway 55 when the sleeve 5 40 is at its lowest position, is an orifice 57. This orifice, it should be noted, opens into the passageway 13 at all times during the movement of the sleeve 40 but the cam 48 is designed to move the orifice 57 into alignment with the 10 passageway 56 when the sleeve is in its upper position.

Diametrically opposed to the ports 55 and 56 is a threaded orifice 58 to receive the conventional type of spark plug 59 therein and an orifice 60 is provided within the sleeve 40 and is designed to come into alignment with the spark when the spark plug is fired as will be presently explained.

The operation of this device is as follows. In 20 the position shown, the sleeve 40 and the piston 52 are at their lowest points and the engine is ready to commence the exhaust stroke. It should here be mentioned that as the cam shaft 25 rotates at only half the speed of the crank shaft, the piston slides within the sleeve 40 and the sleeve within the walls 4. Immediately prior to the piston advancing upwardly, the push rod 34 is raised which opens the valve 18 and thereby allows the gases within the chamber formed by 30 the piston head and sleeve 40 to be expelled through the passageway 13 and through the exhaust port 55.

During the upward movement of the piston, the sleeve 40 is also rising and when the piston 35 reaches its highest point, the orifice 57 moves out of alignment with the port 55 and therefore closes the exhaust port. As the piston now moves downwardly, the sleeve continues to rise and comes into engagement with the intake port 56. 40 The valve 18 is maintained open by the cam 33 and therefore fuel is sucked in through the passageway 13 and into the cylinder.

When the piston again reaches its lowest point, the sleeve will be at its highest point and in this 45 position, the valve 18 closes. The piston now rises for the compression stroke and the sleeve commences to move downwardly. Immediately after the compression stroke is completed, the orifice 60 being in alignment with the spark plug 50 at this time, the spark plug fires and the resulting explosion causes the piston and sleeve to move to the positions shown and the cycle is again repeated.

In the second embodiment of my invention 55 illustrated in Figures 2, 5 and 7 of the drawings accompanying this application, I provide an outwardly bulging crank casing 61 which converges and extends upwardly into a cylinder casing 62 composed of an inner wall 63 and an outer wall 60 63'. The location of these walls provides passageways 64 therebetween which are for the purpose of providing a water jacket around the central cylindrical walls 63 as in my first embodiment.

Upon the upper horizontal surface 65 of the cylinder walls is a gasket 66 and surmounted thereupon, I provide my cylinder head 67. This cylinder head is also double walled in order to allow water to be circulated therein and has a 70 cylindrical portion 68 which extends downwardly into the cylinder formed by the walls 63 which is of smaller diameter than the cylinder to leave a space 68' between the cylinder and the portion 68.

Eccentrically disposed within the cylinder head and extending vertically therethrough is furnished a bushing 69 having a flange 69' adjacent the upper end thereof, this flange seating against the upper surface of the head 67. A valve stem 70 provided with a collar 71 threadably attached to the upper end thereof and a mushroom valve 72 at the lower end thereof is passed through the bushing.

10 A spring 72 identical to the one used in the first embodiment of my invention is interposed between the flange 69 upon the bushing and the collar 71. The valve actuating mechanism, namely, the rocker arm 73, bush rod 74, follower 15 75 and cam 76 upon the cam shaft 77, are all identical to the valve actuating mechanism used in the first embodiment of my invention.

Within the lower portion of the cylinder head 67 is provided a valve seating 78 to receive the valve 72. This seating extends upwardly and branches into two passageways 79 and 80. These passageways, it should be noted, extend upwardly and outwardly and have an obtuse angle between their center lines so that upon reaching the side 25 walls of the cylinder head, the outer orifices of the passageways are diametrically opposed. In alignment with the outer openings at the passageways 79 and 80 within the cylinder head are provided exhaust and inlet ports 81 and 82 respectively which pass through the cylinder walls 63 and 63'.

Adjacent the valve 72 within the cylinder head, is a socket 83 from the lower end of which extends a downwardly threaded orifice 84 designed to 30 receive the usual type of spark plug 85', the sparking tips 86' of which are adjacent the lower end of the orifice 84.

Within the cylinder formed by the walls 63 of the cylinder casing, I provide a snugly fitting 40 cylindrical sleeve 85, the upper end of which is designed to be received within the space 68' between the cylinder head and the wall 63.

A laterally projecting lug 86 is made integral with the lower portion of the sleeve 85 and is 45 provided with a bifurcated end 87.

Immediately below the end 87 of the lug 86 is attached an eccentric 88 upon the cam shaft 77. A split collar 89 encircles the eccentric and an arm 90 attached thereto extends upwardly to be received within the bifurcated end 87 of the 50 lug 86 and is pivotally attached thereto by means of a pin 91 passing through the ends 87 and also through the upper end of the arm 90.

It will now be evident that rotation of the crank shaft 77 will cause a vertical reciprocating motion of the sleeve to occur.

Near the upper end of the sleeve 85 and diametrically opposed therein are two apertures 92 and 93. In the position of the sleeve shown in 60 Figure 2, the aperture 92 is in alignment with the upper end of the passageway 79 and also with the exhaust port 81 so as to provide a continuous passageway therethrough. When the sleeve moves to its extreme upper position, the aperture 65 93 becomes in alignment with the outer end of the passageway 80 and the inlet port 82 but in this position, the aperture 92 will have moved upwardly to close the exhaust port 81.

A piston 94 of the conventional type is inserted 70 within the sleeve 85 and is pivotally attached by the connecting rod 95 to the usual crank shaft. It should here be noted that in this embodiment also, the cam shaft is geared to the crank shaft and is designed to rotate at one half the speed of 75 the crank shaft.

This embodiment of my invention operates in the following manner.

In the position shown, the piston 94 and the sleeve 84 are at their lowest points of travel. Immediately prior to upward movement of the 5 piston, the valve 72 opens and as the piston commences to rise, the sleeve moves upwardly also.

This is the exhaust stroke when gases are forced through the passageway 79, the aperture 10 92 and the port 81. When the piston reaches its highest point, the exhaust port is just cut off by means of the sleeve and the aperture 93 commences to come into alignment between the passageway 80 and the inlet port 82. Thus, on the first 15 downward stroke of the piston, fuel is sucked in through the port 42 and passageway 80 into the cylinder. As the piston again commences to rise, the valve 72 closes and the gases within the cylinder are compressed therein. Shortly after a second 20 downward travel of the piston has commenced, the spark plug 85' fires and the piston is forced to its lowest position where it is again ready for the exhaust stroke and the cycle is thus repeated.

In the third embodiment of my invention illustrated in Figures 3, 4 and 7, I utilize the same type of crank case 96 as in the former embodiments upon which is mounted the usual inner cylinder 97 and outer cylinder 97' between which is the water jacket 98. The usual gasket 99 is 25 placed upon the top of the cylinders and the cylinder head 100 is surmounted thereon. This cylinder head is also provided with passageways 101 therein for the circulation of water for cooling purposes. A circular recess 102 is eccentrically located within the upper end of the cylinder head from the lower end of which extends a vertical orifice 103. A bushing 104 having a flange 105 is inserted within this orifice. A valve stem 106 is passed through this bushing and is provided at its lower end with the usual large mushroom valve 107. The actuating mechanism for this valve is identical with that described in the first two embodiments and it is therefore not necessary to further describe this portion of the 30 invention.

A valve seating 108 is provided in the lower end of the cylinder head to receive the valve 107 and extends upwardly into a passageway 109 which flares outwardly as best illustrated in Figure 4 to 35 provide a wide mouth 110. Adjacent the valve within the cylinder head is located a spark plug in a manner identical to that described in the second embodiment of my invention and shown most clearly in Figure 7.

Within the cylinder 97, I provide a vertically disposed sleeve 111, to the lower end of which is pivoted an arm 112. This arm extends between the cylinder and one leg of a bell crank 113 which is rotatably mounted upon a shaft 114 affixed to 40 the crank case walls. The lower leg of the bell crank is made to bear against an eccentric cam 115 mounted upon the cam shaft 116 by means of a tensile helical spring 117 extending between the bell crank and the crank case.

A detailed view of the type of bearing used at either end of the arm 112 is illustrated in Figure 8. Into the sleeve or bell crank whichever the case may be, is screwed a short stub shaft 118 which is also threaded at its outer end to 70 receive a nut 119. It will be noted that a cross sectional view of the bearing surfaces 120 of the arm 12 are of a convex configuration. This design is to allow a small amount of side play which will occur when the arm 112 is in motion. 75

Instead of utilizing a vertical reciprocating motion of the sleeve in this embodiment, I have designed a means whereby the sleeve may be rotated upon its longitudinal axis as will be evident from the above description of the bell crank and associated mechanism.

At the upper end of the cylinder is located a rectangular aperture 121 having its longer axis disposed in a vertical plane which is designed 10 upon an oscillated motion of the sleeve 111 to move backwardly and forwardly between the side limits of the passageway 109 and thus to come successively into alignment with the exhaust and inlet ports 122 and 123 respectively which pass 15 through the walls of the cylinder.

This embodiment of my invention operates as follows. In the position indicated, the piston is at its lowest position and the passageway 109 opens through the aperture 121 into the exhaust 20 port 122. Upon the piston moving upwardly, the sleeve 111 will commence to rotate and close the port 122 when the piston reaches its highest position. During this operation, the valve 107 has 25 been opened in a manner similar to that described in the former embodiments.

As the piston now commences its first downward movement, the aperture 121 comes into alignment with the intake port 123 and fuel is sucked into the cylinder 111. The valve 107 now 30 closes and the compression stroke commences. Immediately after the completion of this stroke, the spark plug fires and the working stroke takes place whereupon the piston returns to the position indicated in Figure 3 for which the cycle is 35 again repeated.

From the foregoing, it will now be evident that I have provided an extremely simple and ingenious type of internal combustion engine which has the advantage of using only one valve for 40 both intake and exhaust ports and thereby reduces the troubles encountered through the use of valves and also the noise produced thereby. The

single valve also aids in vaporizing the fuel taken into the cylinder and in cooling the exhaust gases expelled from the engine.

Since various modifications can be made in the above invention, and many apparently widely 5 different embodiments of same, made within the scope of the claims without departing from the spirit and scope thereof, it is intended that all matter contained in the accompanying specification shall be interpreted as illustrative only and 10 not in a limiting sense and I desire only such limitations placed thereon as are specifically expressed in the accompanying claim.

What I claim as my invention is:

Improvements in internal combustion engines 15 comprising an engine cylinder, a cylindrical sleeve slidably mounted within said cylinder, a spark plug communicable with the interior of said sleeve, a cylinder head mounted upon said cylinder, a portion thereof being designed to 20 depend into said cylinder, said depending portion being spaced from said cylinder to permit the passage of said sleeve between said dependent portion and said cylinder, a valve operating shaft operated in timed relation with the main crank 25 shaft of the engine, a poppet valve in said cylinder head, a gas inlet and exhaust passageway extending from the periphery of said depending portion and opening against said sleeve valve, said cylinder being provided with intake and 30 exhaust ports therein in alignment with the outer end of the inlet and exhaust passageway, said sleeve being provided with an aperture therein designed to move into alignment between said inlet port and passageway or said exhaust port 35 and passageway during said selected intervals in the cycle of said engine, said sleeve valve being actuated by an eccentric upon said valve operating shaft, said poppet valve being actuated through a push rod and a rocker arm, by a cam 40 also upon said valve operating shaft.

ARTHUR L. REEVES.
